UNITED STATES PATENT OFFICE.

EMANUEL AUFIERO, OF BROOKLYN, NEW YORK.

MECHANICAL HORN.

1,239,425.

Specification of Letters Patent.

Patented Sept. 4, 1917.

Application filed July 23, 1914. Serial No. 852,700.

To all whom it may concern:

Be it known that I, EMANUEL AUFIERO, a citizen of the United States, residing at Brooklyn, in the county of Kings and State of New York, have invented new and useful Improvements in Mechanical Horns, of which the following is a complete specification.

The invention relates to a signal for automobiles, motorcycles and other vehicles; the main object thereof being the construction of signal device easily operated.

In the accompanying drawing, Figure 1, is a partly sectional view of one embodiment of the invention; Fig. 2 is a front view of same.

Similar numbers refer to similar parts in the different views.

An approximately cylindrical casing 1, made preferably of sheet steel drawn to shape, is provided with a flange at right angle thereto having a rim 19 adapted to inclose the corresponding flange 20 at the end of the resonating chamber 2. The vibratory metallic plate 3 is clamped therebetween, the parts being held together by screws or otherwise.

At two diametrically opposite points of casing 1, two adjustable bearings 21 and 22 are provided for a cross-shaft formed with a pinion 6, which moves alternately forward and backward by means of the toothed part 5 fastened to piston 4 which moves in two opposite openings 11 and 11 located on the same casing; the piston being moved downward by the operator and the compression spring 18 returning it to normal.

To said pinion is rigidly fastened the driving ratchet 7 which engages the driving pawl to the freely revolving fly-wheel 16 and diaphragm actuator 9; the spring 10 similarly supported pressing the above named pawl in operative engagement with the ratchet 7.

It is very desirable that the fly-wheel 16 shall be made of relatively thin steel laminations; six laminations about $\frac{1}{16}$ " in thickness, as shown at 15, may be provided. This construction avoids the undesirable, uneven distribution of weight through the mass of the fly-wheel that occurs when a fly-wheel of the same size and material is made of one piece of cast or rolled material. The diaphragm is vibrated by the actuator 9, through the wearpiece 14 in engagement therewith. A stud 12 is provided for said

wearpiece having a shoulder 25 of smaller diameter than the diameter of washer 13 on which said stud is riveted. It is found in practice that this arrangement will prevent 60 a fracture of the diaphragm near the clamped edge of the wear-piece supporting members.

In horns of this character the cheapness of construction and simplicity of operation 65 are of prime importance. By the above described construction I obtain a direct application of power to the serrated disk without intermediate gearing of any kind. The elimination of the intermediate gearing 70 permits the serrated disk to occupy the full dimensions of the casing, and also permits the rack to have the fullest stroke possible in a standard size casing. The large size disk makes possible the use of a fly wheel 75 of maximum diameter whereby the rotation of the disk will be maintained during the return movement of the rack by its momentum alone.

By those skilled in the art, many changes 80 and substitutions may be made without departing from the scope of the claims.

What I claim is:

1. In a mechanical horn, the combination of a vibratory diaphragm, a casing having one end closed by said diaphragm, a shaft supported in said casing with its axis parallel to the plane of said diaphragm, a pinion on said shaft, a heavily weighted serrated disk having operative connection with said diaphragm mounted upon said shaft and rotatable independently of said pinion, a one-way clutch connection for transmitting motion from said pinion to said disk and a rack mounted for reciprocation in the wall of said casing and having operating engagement with said pinion. 85 90 95

2. In a mechanical horn, the combination of a resonating chamber, a casing secured to said chamber, a vibratory diaphragm mounted between said chamber and casing, a shaft mounted for rotation in said casing having its axis parallel to the plane of said diaphragm, a pinion on said shaft, a heavily weighted disk having peripheral serrations 100 105 freely mounted on said shaft, a wear piece carried by said diaphragm and engaging said serrations, a pawl and ratchet connection between said disk and shaft and a manually operable rack engaging said pinion 110 and supported in said casing for reciprocating movement in a plane parallel to said

diaphragm and at right angles to said shaft.

3. In a mechanical horn, the combination of a vibratory diaphragm, a cylindrical casing, having one end closed by said diaphragm, a shaft supported in said casing with its axis parallel to the plane of said diaphragm, a pinion on said shaft, a disk provided with peripheral serrations freely mounted on said shaft, an annular weight of an outside diameter substantially equal to the solid portion of said disk attached to said disk, a wear piece mounted in said diaphragm and engaging said serrations, a pawl and ratchet connection between said disk and shaft and a manually operable rack mounted for reciprocation in said casing and engaging said pinion.

4. In a mechanical horn, the combination of a vibratory diaphragm, a casing having one end closed by said diaphragm, a weighted serrated disk supported within said casing for rotation about an axis parallel with the plane of said diaphragm, a pinion supported within said casing adjacent said disk for rotation about the same axis, a one way clutch connection for transmitting motion from said pinion to said disk and a reciprocating rack supported with its teeth in engagement with said pinion, said rack projecting beyond said casing to facilitate its operation.

EMANUEL AUFIERO.
